UNITED STATES PATENT OFFICE.

JOHN R. BOYD, OF CINCINNATI, OHIO.

SHAFT AND HARNESS BUCKLE.

SPECIFICATION forming part of Letters Patent No. 645,064, dated March 13, 1900.

Application filed April 19, 1897. Serial No. 632,727. (No model.)

To all whom it may concern:

Be it known that I, JOHN R. BOYD, a citizen of the United States, and a resident of the city of Cincinnati, in the county of Hamilton and State of Ohio, have invented certain new and useful Improvements in Shaft and Harness Buckles, of which the following is a specification.

The primary general object of my invention is to provide a simple and durable mechanism intermediate between the harness and the shaft and which shall be readily attached to the shaft, thereby coupling the harness to the shaft, and which when attached shall remain attached until detached by human agency and which shall be in the latter event readily disconnected from the shaft.

Another object of my invention is to produce a mechanism which shall in no wise come in contact with the horse.

Still another object of my invention is to provide means whereby this connection of the harness to the shaft shall not operate to compel the horse to pull the vehicle by the saddle, but, on the contrary, shall leave the saddle as free as if traces were used in connection with a singletree.

Other objects of my invention will be hereinafter apparent.

The several features of my invention and the various advantages resulting from their use, conjointly or otherwise, will be apparent from the following specification and claims.

In the accompanying drawings, making a part of this specification, Figure 1 represents an elevation of a mechanism and of a part of a shaft to which said mechanism is connected. Fig. 2 is a view looking down on this mechanism, all of the latter above a plane passed through the dotted line 2 2 of Fig. 1 being removed to disclose certain parts of the construction. Fig. 3 is a longitudinal sectional view of the latch similar to that shown in Fig. 2, but showing the latch open, (unlocked,) whereas in Fig. 2 it is shown as locked. Fig. 4 is a top view of the spring mechanism and a part of that hinge which connects the same to the buckle. Fig. 5 is a side elevation of the buckle or main frame-piece of the devices in question. Fig. 6 is a vertical section of the buckle and latch-catch with hook, on a diminished scale, taken in

the plane of the dotted line 6 6 of Fig. 1, that side of the section being seen which faces toward the left in Fig. 1. Fig. 7 is a side elevation of the bar used in attaching the catch-latch to the shaft.

In order to fully understand the nature of my invention, it is to be noted that my improvements belong in general to that class of attachments which draw the road-vehicle by the shafts and dispense with the singletree and the shaft-tugs, which latter are attached to the bearing-straps of the saddle in the old-style harness. My invention therefore has in common with the prior devices of its class the following advantages: It effects a saving in the use of shaft-harness. It precludes the wearing of the trace, which occurs when singletree and trace connected thereto are employed. It prevents the wearing of the tugs by the shafts, and vice versa. Thereby the duration of the harness and shafts is greatly lengthened. It also prevents the rocking to and fro of the four wheels, which is caused by the old-style harness by virtue of pulling from the center of the singletree. This is a great advantage, because with the old style of harness the horse pulls from the center of the singletree, and if either wheel strikes a resisting substance it is necessary that the same weight or power is pulled against the wheel not obstructed as the one which is obstructed, thereby resulting in a shake-up of the horse, a shaking up of the shafts, and the rattling of both wheels at the expense of the fifth-wheel.

It is also to be noted that by the draft directly from and by the shaft in the vicinity of the vertical plane of the saddle a horse in pulling a buggy has twenty-eight per cent. greater power of draft than he would possess by the old-style harness. In pulling by the old-style singletree there is necessarily some pressure on the horse's back, as the tree when pulled presses down the forward portion of the shafts, and they in turn through the medium of the saddle-straps pull the saddle down on the horse's back.

In the class of devices to which my improvements belong there is absolutely no weight whatever on the horse's back, as the shafts are always lifted slightly upward.

In descending hills, where the old style of

harness is used, there is a strong tendency of the front end shafts to fly upward, due to the fact that the holdback-straps are attached to the shafts near the flank of the horse and when the horse is sitting on the breeching they (the shafts) are naturally thrown upward, rendering a strong undergirth absolutely necessary.

When the draft-harness buckle having the backing-straps (breeching) is fastened to the shaft opposite the saddle, as in the class of constructions in which my invention is included, the shafts are held on a level when descending hills, precluding the possibilities of their flying upward and rendering the presence of the undergirth unnecessary.

Still another advantage resulting from the attachment of the draft and backing connections to the shaft at or near the saddle consists in the fact that with such connection the pulling is from near the free end of the shaft, thus giving a long leverage, whereas in the old way the horse is compelled to press the shafts around the shoulders, at the same time pulling from the center of the single-tree, which necessarily pulls as much against one wheel as the other.

In all of these advantages my invention participates, and it enjoys some of these advantages in a greater degree than in other prior devices of its class. These increased advantages and other and most valuable advantages which my invention and its features possess over anything and everything that has preceded it will be fully hereinafter set forth.

I will now proceed to describe my invention in detail.

A indicates the main frame, constructed as follows: In practice the length of the upper bar A² is substantially parallel to the ground, and the same is true of the lower bar A³. The middle portion has a bar A⁴, which forms the pivotal connection with the hereinafter-described elastic or spring connection S, intervening between the main frame or buckle piece A and the strap W, which is connected to the hame or breast-collar. This main frame has a bar A⁵, adapted to receive and engage with the catch D, hereinafter described. The bars A⁴ and A⁵ are connected to the bars A⁶ and A⁷ of the frame A. The bars A⁴ and A⁵ are at right angles with the line of the shaft, as it is in this direction the draft from the horse is exerted. The bars A⁴ and A⁵ are therefore at other than a right angle with the bars A² and A³. The bars A² A³ are connected with the parts A⁶ and A⁷ by suitable end pieces, as A⁹ and A¹⁰. In the rear of the main piece A is the bar or piece A¹², parallel to bar A⁵, and this piece A¹² receives the rear end of the latch. The rear end of the main frame or buckle A is provided with an extension A⁶ A⁷ A¹³, and to the bar A¹³ is connected the strap T, which is connected to the backing-straps. To prevent the line of attachments consisting of the strap

W, spring connection S, main frame A, strap T, and the backing-straps from sagging down at any time, either when connected with the shafts or disconnected therefrom, I provide the suspensory device B, having buckle for connection to the saddle-strap B² and extension B³, whose sides embrace the rod A² of the main frame A and carry the grooved roller B⁴. It is on the latter that the rod A² of the main frame rests and slides. Below on the lower rod A³ of the frame A is a roller C⁴, journaled in parallel pieces of extension C³, connected to loop C² or other device, whereby the entire device C is connected to the undergirth or belly-band. It is on the roller C⁴ of this device C that the rod A³ of frame A runs. This sliding bar of the buckle, in combination with the roller or wheel, works as easily as required and precludes positively the possibility of any and all weight being placed on the horse's back in going down-hill. The sliding bars are arranged as shown, so that the bearing-straps of the saddle will slide either forward or backward, as may be required, to alleviate entirely any pressure or friction on the horse's back. These advantages also inure in relation to the undergirth as it is attached to similar sliding bars. No pressure from the shafts is therefore communicated to the belly of the horse.

It will be observed that the location of the bars A² and A³ horizontally enables them to best serve the purpose of relieving the saddle and undergirth from pulling strains and that the location of the rods A⁴ and A⁵ and A¹³ at an angle to the vertical—viz., at right angles to the line of draft—best subserves the purpose of a draft on the horse in the line of the shafts.

I provide the extension A⁶ A⁷ A¹³ at the rear of the buckle and make it of some length, and thus assist in keeping the side harness away from the horse's side when the latter is backing.

The connection between the buckle A and the front strap W is made by the spring attachment S. This attachment consists of a frame having the bars S² S² connected at the front end to the cross-piece S³ and to the rear end and the hinge cross-piece S⁴ pivotally connected, as aforementioned, to the pivot brace-rod A⁴. On the bars S² slides the cross brace or bar S⁶, and to the latter is a bar S⁵, slidable through bar S³ and connected at its rear end to the cross-brace S⁴ and at its front end to the link S⁷, to which the strap W is attached. The brace S⁶ is slidable on bars S² S². Each of the bars S² S² and S⁵ carries a coiled spring S⁸, and these springs lie between the cross-bars S³ and S⁶. While the horse is drawing the vehicle, the strap W, pulling on the bar S⁵, draws the bar S⁶ forward against the springs S⁸ and compresses them more or less, according to the weight of the vehicle, its load, and the resistance of the road.

It is to be noted that the rear end side of the piece S⁴, above and below where it meets

the extensions A⁶ E A⁶ E of the bars A⁶, is squared to a certain extent and so close to these extensions that only a limited extent of oscillation of the spring attachment is permitted in relation to the buckle A. When the harness-buckle A is attached to the shaft, the shape of the buckle, in conjunction with the spring attachment, is such that in turning the tendency is to press the shafts just a little outward, thereby rendering the chafing of the horse impossible. So, also, when the horse, with harness, is detached from the shafts the stop connection between the shaft attachment and spring prevents the joint between the two from bowing in toward the horse and chafing him. The spring attachment in front of each buckle relieves the shoulder motion of the horse and relieves all jar to the horse by obstruction to the wheels in travel.

The construction of the catch is as follows: D is the body, hollow for the purpose of receiving and holding the reciprocatory rod D² of the latch. Around this rod is coiled the spring D⁵, which latter rests against an abutment D⁸ at the rear end of the body D. Near the front end is a collar D⁴, fixed thereon, and the spring is compressed by pulling back the rod D². The rear end of the rod D² is connected to or provided with a means for pulling back the rod, and this means is preferably a link D²¹, swiveled at D⁶ to the rod D². The rod can be pulled by taking hold of this link or eye D²¹ by the hand or connecting to this link or eye D²¹ a strap or cord D⁷, extending back to the vehicle-body and having its rear terminal (or additional connections thereof) within reach of the occupant of the vehicle. The forward end of the body D has an enlarged hollow portion D⁸ open at D⁹ on the side toward the horse, and in this opening D⁹ is located the oscillatory catch D¹⁰, extending into the head D⁸, as shown, and pivotally connected to the body D by the pivot D¹². The rear part of the catch-piece carries an extension or tail D¹³, which when the catch is closed rests against the front end of the latch-rod D², as shown in Fig. 2. The front end of the catch D¹⁰ has a recess D¹⁴ to receive the vertical brace and has two jaws or extensions D¹⁵ and D¹⁶, which respectively bound this recess. When the catch is closed, the forward part of the jaw D¹⁵ is alongside of the adjacent front wall of the head D⁸ and the other jaw D¹⁶ is within the head D⁸, as shown, and the bar A⁵ of the buckle A is embraced between the catch and front wall of the head. There is a spring D¹⁷ of a coiled part and two limb parts, the coiled part located in and held in a recess D¹⁸ of the head, as shown. One limb of this spring rests in a recess D¹⁹ in the jaw D¹⁶ and bears elastically against the latter, while the other bears against that part of the head which is opposite the opening D⁹. When the latch-rod D² is drawn back, as in Fig. 3, the spring D¹⁷

throws the catch out and holds the latter open, as shown in Fig. 3. To lock the catch, the bar A⁵ of the buckle A is placed in the recess D¹⁴ and the buckle pressed, so that the bar A⁵ is pushed into the head D⁸. The bar A⁵ thus pressed carries with it the catch D¹⁰ by pressing jaw D¹⁶ still farther into the hollow of the head D¹⁹. When the bar A⁵ and the catch have reached the position shown in Fig. 2, (which they will do almost instantly,) the spring D¹⁷ will be compressed, and the extension D¹³ of the catch being moved out from interference with the latch-rod D² the latter will move forward toward pivot D¹² and alongside of the extension D¹³, and thus lock it in position, thereby securely locking the latch in the position shown in Fig. 2. Thus the buckle A will be held to the catch, and the catch fixed in body D D⁸ will remain unmoved, and the body D D⁸ being duly fixed to the shaft the horse will draw the vehicle by his pull on the front end of the catch and will back the vehicle or hold it back on a descent by the bar pressing on the back side of the recess D¹⁴ of the catch. To hold the buckle A in the proper position relative to the catch, shaft-harness, and horse, the hook D²⁰ is provided and attached to that side of the catch next to the horse. In applying the buckle to the catch the bar A¹² of the buckle is first brought within the embrace of the hook D²⁰, and then the bar A⁵ is introduced into the recess of the catch and the latter locked upon and around the bar A⁵. Attention is called to the fact that the construction and arrangement of the parts are such that when the strain comes upon the buckle and catch from the breeching, as when the horse is backing the vehicle or holding it back, the pull is on the back part of the catch and in such a direction as not to open it, but to keep it closed. Thus this strain is taken by the parts in a safe and secure manner.

In opening the catch the latch-rod D² is pulled back, and its forward end will leave the extension D¹³ of the catch free to move, and the spring D¹⁷ will open the catch. When the pull on the latch-rod is released, the latter will advance until the forward end strikes against the rear end of this extension D¹³ (see Fig. 3) and will stay there until the catch is closed, as aforementioned. Then the parts will again assume the position shown in Figs. 1 and 2.

There are various ways in which the catching and latching device may be attached to the shaft. I prefer to employ an exceedingly useful as well as novel means for this purpose, inasmuch as these means confer important advantages, hereinafter specified.

The body-piece D D⁸ is provided with lugs E E to rest on the shaft. Each of these lugs has a perforation E², and thereby the lug can be fixed to the shaft by a bolt through the latter; but in my preferred mode I take a bar E³ and provide the under side with detents

E^4 , one detent for each lug. The detents respectively fit the perforations in the lugs. A depressed prominent portion E^5 on the bar E fits down between the lugs and against the shaft. This portion E^5 carries one or more teeth E^6 . The bar is clamped down to the shaft, the detents E^4 in the lugs and the teeth E^6 entering the shaft. The teeth prevent the bar from slipping on the shaft, and the bar E holds the body D D^8 of the catch-latch in place. By these means the latter can be moved along the shaft back or forth and then be quickly clamped in place to adapt it to be connected to the harness of a long or short horse, as the case may be. The preferred clamp is the well-known cuff-clamp, having band E^7 and cross-bar E^8 , (below shaft,) held to the screw extensions of the band by nuts E^9 . The top of the clamp sets in a depression E^{10} of the bar E^3 . When preferred, the bar E^3 may be cast in one with the lugs E . It should also be noted that the bar E^3 may be clamped on the shaft nearer to or farther from the inner edge of the latter. Thus the buckle may be kept at a proper distance from the side of the horse, be he thick or thin.

When desired, the tooth or teeth E^6 may be on the lugs instead of on the bar.

The middle portion of the bar E may have 30 end detents or shoulders E^{12} . Between these the cuff-clamp may loosely fit, thereby making a close engagement therewith.

What I claim as new and of my invention, and desire to secure by Letters Patent, is—

1. The draft-buckle having the cross draft-bar A^5 , and the rear holding-bar A^{12} , and the rear extensions A^6 , A^7 , A^{13} , substantially as and for the purposes specified. 35

2. The combination of the latch-catch, body D , D^8 , lugs E , E , and bar E^3 , having detents, 40 within the lugs, and a tooth or teeth for engaging the shaft, substantially as and for the purposes specified.

3. The combination of the latch-catch, body D , D^8 , lugs E , E , and bar E^3 , engaging the lugs 45 and having depression E^{10} , and the tooth or teeth on its side next the shaft, substantially as and for the purposes specified.

4. The combination of the body D , D^8 , having the latch-catch, lugs E , bar engaging said 50 lugs, and a device for engaging said shaft, and preventing the catch, &c., from slipping on the shaft, and a suitable clamp, substantially as and for the purposes specified.

5. The combination of the body D , D^8 , having the catch with latch, lugs, bar-engaging lugs and having shoulders E^{12} and part for 55 engaging the shaft, and tooth, substantially as and for the purposes specified.

JOHN R. BOYD.
